UNITED STATES PATENT OFFICE

BERTRAM M. MILLS, OF PAWTUCKET, RHODE ISLAND, ASSIGNOR TO THE STANDARD ENGINEERING WORKS, OF PAWTUCKET, RHODE ISLAND, A CORPORATION OF RHODE ISLAND

DESIGN FOR A HUMIDIFIER CASING

Application filed October 9, 1930. Serial No. 37,199. Term of patent 14 years.

To all whom it may concern:

Be it known that I, BERTRAM M. MILLS, a citizen of the United States, residing in Pawtucket, in the county of Pawtucket, State of Rhode Island, have invented a new, original, and ornamental Design for a Humidifier Casing, of which the following is a specification, when taken in connection with the accompanying drawings, of which—

Fig. 1 is a perspective view of a humidifier casing showing my new design; and
Fig. 2 is a side elevation of the casing.

I claim:

The ornamental design for a humidifier casing substantially as shown.
